CLAIM

The ornamental design for a range extender device, as shown and described.

DESCRIPTION

FIG. 1 is a top, front, right-side perspective view of a first embodiment of a range extender device;

FIG. 2 is a bottom, back, right-side perspective view thereof;

FIG. 3 is a bottom, back, left-side perspective view thereof;

FIG. 4 is a front view thereof;

FIG. 5 is a back view thereof;

FIG. 6 is a left-side view thereof;

FIG. 7 is a right-side view thereof;

FIG. 8 is a top view thereof;

FIG. 9 is a bottom view thereof;

FIG. 10 is a top, front, right-side perspective view of a second embodiment of a range extender device;

FIG. 11 is a bottom, back, right-side perspective view thereof;

FIG. 12 is a bottom, back, left-side perspective view thereof;

FIG. 13 is a front view thereof;

FIG. 14 is a back view thereof;

FIG. 15 is a left-side view thereof;

FIG. 16 is a right-side view thereof;

FIG. 17 is a top view thereof; and,

FIG. 18 is a bottom view thereof.

The broken lines depict portions of the range extender device that form no part of the claimed design.

The stippling and oblique line shading shown on the respective surface portions of the range extender device of the second embodiment define contrasting surfaces.

1 Claim, 18 Drawing Sheets
